TIME REMINDING DEVICE

Helen Sargent Hitchcock, New York, N. Y.

Application January 16, 1933. Serial No. 651,973

2 Claims. (Cl. 116—121)

My present invention refers to certain new and useful improvements in timing or reminding devices for nurses, patients and others, that are usually capable of being set to indicate when a predetermined interval of time has elapsed, or when the point of time arrives when a future event is to take place or an act to be performed, such as for example the taking of the next dose of medicine by a sick person, or the performance 10 of the next act in a recurrent series of acts at specified intervals apart, some one of which acts might be overlooked if the memory alone were depended upon to advise as to the appointed time for such act, or the time for the taking of such 15 medicine. The usefulness of such a reminding device is greatly increased by constructing the device in a form or design which will attract and amuse the patient, especially when such patient is a child, by captivating the watchful attention 20 and thus more effectually ensuring a recognition of the time when the next dose is due or another act is to be performed.

The invention consists essentially in combination with a timepiece dial of any kind having a face on which units of time are marked and employing movable hands or pointers that measure or indicate the time, of a separate, distinct and independent device that is adapted to be removably attached by suction means or otherwise to 30 the face of the timepiece and which carries an adjustable hand or pointer which is adapted to be fixedly pointed at or to the hour or time at which the next medicine dose is due, or at which some time interval will be concluded and some act is due 35 to be performed. The suction means may be designed in form of a small animal, as a rodent, bird, or other living creature, or as a conventional figure, ornament, design, or button, provided only that it has a suction cup and a hand or pointer 40 mounted thereon, the hand being adjustable as to its effective length.

And the invention also comprises numerous details and peculiarities in the construction, combination and arrangement of parts, substantially 45 as will be hereinafter described and claimed.

In the accompanying drawing illustrating my invention:

Figure 1 is a front elevation of my improved timing device, shown as practically applied to 50 the face of a clock.

Figure 2 is a cross-sectional elevation of the same.

Figure 3 is a sectional view of an alternative form of suction holder.

Figure 4 is a plan view of the same.

Similar characters of reference designate corresponding parts in the different figures of the drawing.

1 denotes a clock dial or face, covered by glass 1a, said dial having the usual hands, as hour 60 hand 2 and minute hand 3, the dial being marked with the usual time numerals of any kind and minute graduations. This is only one example of a clock or timepiece. My invention is general and can be applied to any timepiece used for 65 marking time.

4 denotes a body device or member that has a suction cup on one side at 7 and carries a hand or pointer 5 which is designed to point to one of the hour numerals or minute degrees, or both, as 70 shown on the dial 1 near its periphery, so that by attaching the suction cup 7 to the dial glass 1a the device 4 can be located in some central or other position over the dial face 1 with hand 5 in a stationary position, pointing at some one 75 of the dial figures.

The suction member 4 may take a variety of different forms. In Figure 1 it is made in the form of a mouse having on the under side a concave recess 7 in the rubber or other material of 80 which the mouse is made. The suction of cavity 7 when the mouse image is pressed tightly against the face of glass 1a causes the mouse to adhere or stick closely to the clock. The mouse can at any time be readily detached from clock 85 dial by slightly lifting the edge of the recess 7 and allowing air to enter and break the vacuum so that the mouse can be loosened and removed.

Running through the solid rubber body of the mouse 4, by being imbedded therein when mold- 90 ed, above the cavity 7 is a pointer or hand 5 which projects a distance from mouse, outwardly or rearwardly or otherwise as preferred. This hand 5 has a spiral section 6 where it enters the body of the mouse, so that it can screw into said 95 body for a greater or less distance and in this way the length of hand or pointer projecting outside of and away from the mouse-figure can be changed at will to enable the hand to be varied in length to correspond with the different length 100 of radius of various clock faces with which the timing device may be used.

Instead of an animal figure of which the little rodent 4 is an example, the suction member may be a round button, as 8, having a suction cavity 105 9 and operating in a manner similar to the mouse figure. The hand 5a having a spirally bent section 6a is passed screwlike through a cap or protuberance on the button 8 and allowed to project one or both ways, one end pointing to the 110

time units of the dial. This button may be of any form, and in any conventional shape or design.

The rather novel and fanciful appearance of 5 a mouse design or other little animal on the face of a clock dial will catch the thought and hold the gaze of a child, and even an older person, so that the mind will be kept on the pointer and the time reading that it is set to mark. For the 10 child might suppose the mouse to be alive and might watch to see it jump or move, and thus the attention would be concentrated on the clock. And from the fact that the child or patient has his attention held and is amused by something 15 curious, the nurse or patient will be apt to notice also what the patient is noticing, so that the time interval will be watched and the time for the next medicine or act will not be overlooked.

Obviously the mouse may have any form and 20 shape, and other little animals of many breeds and kinds may be substituted, or plain designs of still forms, provided the same can carry a suction means to enable it to be fastened firmly

and quickly on a dial glass and provided also that it can hold an adjustable finger which may direct the attention to a time figure at which an act is to be performed. Therefore the invention will be found to have a wide variety of applications. And even outside of the suggested field a pointer that can be removably attached to a clock crystal to note the future time for doing some act will be found of much value and service.

What I claim, is:

1. In a reminding device, the combination with a timepiece dial, of a body having suction means to attach it to the dial, and a time-indicating stationary pointer carried by the body and formed with a spiral section that screws into the body and adjusts the length of the pointer relatively to the radius of the dial.

2. In a device of the class described, a clock face, a body having suction means to attach it thereto, and a time pointer screwed adjustably into the body so as to vary the length of the pointer.

HELEN SARGENT HITCHCOCK.
